Primary Examiner — Mitchell I. Siegel(74) *Attorney, Agent, or Firm* — Payam Moradian(57) **CLAIM**

I claim the ornamental design for a guitar case, as shown and described.

DESCRIPTION

FIG. 1 is a front perspective view of the guitar case showing my new design;

FIG. 2 is a front view thereof;

FIG. 3 is a rear view thereof;

FIG. 4 is a left side view thereof;

FIG. 5 is a right side view thereof;

FIG. 6 is an end view thereof;

FIG. 7 is an opposite end view thereof; and,

FIG. 8 is another front view thereof.

The broken lines shown are included for the purpose of illustrating unclaimed subject matter and forms no part of the claimed design.
